H. TER KUILE,
REPLENISHING MECHANISM FOR MULTICOLOR LOOMS.
APPLICATION FILED JUNE 16, 1920.

1,423,279.

Patented July 18, 1922.

2 SHEETS—SHEET 1.

Inventor-
Harry ter Kuile,
By- B. Duyer, Atty.

UNITED STATES PATENT OFFICE.

HARRY TER KUILE, OF ENSCHEDE, NETHERLANDS.

REPLENISHING MECHANISM FOR MULTICOLOR LOOMS.

1,423,279.

Specification of Letters Patent. Patented July 18, 1922.

Application filed June 16, 1920. Serial No. 389,432.

To all whom it may concern:

Be it known that I, HARRY TER KUILE, manufacturer, a subject of the Queen of the Netherlands, residing at Enschede, the 5 Netherlands, have invented certain new and useful Improvements in Replenishing Mechanism for Multicolor Looms, of which the following is a specification.

This invention relates to an automatical 10 cop substituting device for change-box weaving looms, and has as an object to provide a simplified mechanism for automatically substituting the cops in change-box weaving looms.

15 A further object is a mechanism with which the substitution of the cops takes place during the upward movement of the slay which follows upon the changing of the position of the change-box. This is obtained by means of a very simplified mechanism.

In the accompanying drawings which illustrate my invention,

20 Fig. 1 is a side elevation of the arrangement applied to a revolving circular change-box loom, seen from the left hand side of the loom,

25 Fig. 2 is a corresponding side elevation seen from the right hand side of the loom, and

30 Fig. 3 is a front elevation of the same arrangement.

In the drawings, 1 is the revolving change-box. Each compartment of this change-box 35 is provided with an electric feeler arrangement, of the type shown in American Patent No. 1,330,036, granted to me, the contact bow and contact spring 21 of which are shown in the accompanying drawings.

40 An electrical connection with a separate contact plate 22 is provided for every bow 2. At a determined point, the contact plates 22 connected with the change-box compartment, are contacting with a sliding contact 45 spring 3 in such a way, that when such a contact plate 22 is in operation, it contacts with the sliding contact spring 3 which is electrically connected with a contact-brush 23, the latter pressing against the periphery 50 of a contact disc 4, which revolves with the bottom shaft of the loom. The contact disc 4 is provided with a contact strip 25, which has a determined length and which co-operates with a second contact brush 24. At 55 a certain moment which is determined by the length and by the position of the contact-

strip 25 and by the respective positions of the brushes 24, 23, an electrical connection of the brushes 23 and 24 occurs. The contact brush 24 is electrically connected with a 60 magnet coil 5, another conducting wire connecting the magnet coil 5 with one of the poles of a source of electric current, whilst the second pole of said source is electrically connected with the contact-strip 21 in each 65 compartment of the change-box.

One of the outer ends of a pawl or catch 6 is situated underneath the magnet coil, which pawl is rotatable around a bolt 26, the latter being fixed to a rod 9. When 70 an electric current flows through the magnet coil, the latter attracts the outer end of the pawl 6, which is situated underneath it, whereby the other end of the pawl comes into such a position that it is able to engage 75 a rocking hook 27, which forms one of the outer ends of a bell-crank lever 7. This bell-crank lever is rotatably mounted on a shaft 28, and its second arm is supported by an eccentrical disc 8 which co-operates with 80 the bell crank lever in such a way, that the latter is caused to rock to and fro when the bottom shaft revolves.

The cop-store 29 is hingedly connected with an axis 31, and is divided by means 85 of a partition wall 30 into two compartments, each containing cops of a determined kind or color. The cop-store 29 is disposed above the path of the fixed shuttle-box in such a way, that the shuttle-box 34 is situated 90 perpendicularly underneath the cop-store at the moment when the slay has reached its utmost forward position.

A transferring hammer 10 which is rotatable around a fixed axis cooperates with 95 the cop-store 29 and is hingedly connected to an arm 11. The arm 11 is connected with the rod 9 by means of a lever system, (not shown), in a known manner. (German Patent No. 289,542). When the rod 9 is moved 100 back-wards, (to the right in Fig. 2,) the arm 11 will be raised, (shown in dotted lines in Fig. 2), thereby engaging the stud 32, which is fixed on the slay. This occurs when the slay is beaten up, in which case the stud 32 105 pushes the arm 11 forward (to the left in Fig. 2), whereby the transferring hammer 10 expels a cop from the cop-store and pushes it in the known way into the shuttle, at the moment the latter is present in the shuttle- 110 box underneath the cop-store.

The following mechanism has been pro-

vided in order to press a cop of the desired color or kind into the shuttle.

A cam disc 20 has been provided co-axially to and revolving with the shuttle-box 1. 5 This cam disc 20 has a recess at those places which correspond with the compartments of the shuttle-box containing cops of the same color or kind as those contained in the rear compartment of the cop-store 29, (left portion in Fig. 2).

A rod 19 presses by means of a spring or the like against the cam disc 20, the rod 19 being hingedly connected to the lever 18. The lever 18, 16, is mounted upon the shaft 15 17. Said lever 16, 18, is at its other end hingedly connected with a vertical rod 15.

The cop store 29 is hingedly connected to a lever 12, by means of a rod 33. The lever 12 is suspended at its upper end in the same 20 way as a pendulum. A hook 13 is hingedly connected to the lower end of the suspended rod 33. The hook 13 is supported by the rod 15.

The rod 9 is provided with a stud 14, 25 which is able to engage the hook 13 when the rod 15 is in its lower position.

The apparatus acts in the following way:

When the slay has reached its foremost position, and another color is wanted, the 30 position of the change-box will be changed. After this changing has occurred, the slay immediately goes backwards. At this moment, (that is to say before the crank of the crank-shaft of the loom has reached its 35 lowest position) the feeler arrangement enters into active operation which is possible because at that moment the contact-strip 25 connects the contact brushes 23 and 24 electrically. If at the same time the cop, 40 which is present in the respective change-box compartment is sufficiently exhausted of yarn to enable an electric current to flow from the contact-spring 21 through the shuttle, to the contact-bow 2, then the magnet coil 5 will be energized.

This causes the pawl 6 to be attracted by the magnet-coil. At the same moment the hook 27 is moving backwards to the right in Fig. 2, and engages the pawl or catch 6, so 50 that the latter is pushed backwards too. The pawl 6 also pushes the rod 9, on which it is mounted, backwards. This causes the arm 11 to ascend, so that it comes in front of the stud 32, which is mounted on the slay. By 55 the now occurring beating-up of the slay, the stud 32 presses the arm 11 forward, which occasions the transferring hammer to press a new cop into the shuttle, which at this moment is in position underneath the cop store 60 compartment in action.

The slay will then swing backwards, and the stud 32 leave the arm 11 free, so that the transferring hammer moves upwards.

If the position of the change-boxes has 65 been changed just before the pawl 6 has

been attracted by the magnet coil, the cam disc 20 will have been rotated at the same time with the revolving change-box and comes into a new position. If at this moment the rod 19 enters into a recess of the 70 cam disc 20, it consequently ascends to the depth of the recess, which causes the lever 18 to rise too. Consequently, the lever 16 descends, whereby also the rod 15 descends, so that the hook 13 engages the stud 14 on 75 the rod 9.

During the following backward movement of the rod 9, (towards the right in Fig. 2,) the stud 14 moves the hook 13 backwards, which also occasions the movement of 80 lever 12 and rod 33 in a backward direction, so that the cop-store will be moved to the right in Fig. 2, till the opening in the bottom of the front section or compartment of same is positioned perpendicularly 85 underneath the outer end of the transferring hammer 10. In this way, the suitable compartment of the cop store can be brought underneath the transferring hammer, so that the desired cop-substitution takes place. 90

If on the contrary, after the changing of the position of the change-boxes, the rod 19 presses against a cam portion of the cam disc 20, the rod 19 will be pulled down to its lower position, whereby the rod 15 will 95 ascend to its upper position by means of the levers 18 and 16, so that the hook 13 also ascends, and thus remains out of engagement with the stud 14 on the rod 9. This causes the cop-store to remain in its 100 normal position, i. e. in such a position that the opening at the bottom of its rear compartment behind the partition wall 30, remains perpendicularly underneath the outer 105 end of the transferring hammer 10.

It is evident that the cam disc 20 may be substituted by any suitable means for actuating the rod 19 of the lever system 19, 18, 16, 15.

The cam disc 20 may for instance be 110 fixed on a separate axis moved by means of a gear, which is operated by the change box.

Having fully described my invention, what I claim is:

1. Automatic cops substituting mechanism comprising a cops store mounted for movement, a movable cops ejecting element, an operating rod, means for moving the cops store including a member arranged for engagement with and disengagement from said operating rod, means operated by a loom shaft for moving said operating rod, a member carried by said rod to engage and disengage said loom shaft operated means, an electro-magnet to move said engaging means 115 to engaging position, circuit closing means including a member moved by said loom shaft, and means to normally hold said member of the cops store moving means out of engagement with the operating rod, a change 120

box having an electric feeler, including a contact bow and a contact member for each of its compartments, and an electric circuit including the windings of said electro-magnet, said relatively fixed contacts, and a contact for successive engagement with the contact members of the change box.

2. Automatic cops substituting mechanism comprising a cops store mounted for swinging movement, a movable cops ejecting element, means for moving the cops store including a member arranged for engagement with and disengagement from said operating rod, a loom shaft, an oscillating member, said shaft and said member having means to cause said member to be oscillated by said shaft, a pawl mounted on said rod, an elec-

tro-magnet to cause said pawl to engage said oscillating member, circuit closing means including a member moved by said loom shaft, and means to normally hold said member of the cops store moving means out of engagement with the operating rod, a change box having an electric feeler, including a contact bow and a contact member for each of its compartments, and an electric circuit including the windings of said electro-magnet, said relatively fixed contacts, and a contact for successive engagement with the contact members of the change box.

Signed by me, at The Hague, this second day of June, 1920.

HARRY TER KUILE.
